DIFFERENTIAL ACTUATING AND PRINTING MECHANISM FOR AN ACCOUNTING MACHINE

Charles A. Parker, Knoxville, Tenn., and Clifton K. Rainey, Chicago, Ill., assignors, by mesne assignments, to Burroughs Corporation, a corporation of Michigan

Application May 25, 1951, Serial No. 228,274

28 Claims. (Cl. 235—60.28)

This invention relates to accounting machines. It provides a single machine operative under selective control to function as either a typing machine, a posting machine, or a calculating machine, in which all typing and all calculator indexing operations are governed from a common, single keyboard. Incidental to the performance of its various functions, the machine embodies the usual manual and automatic controls of known typewriting, posting, and calculating machines; and additionally includes novel manual as well as automatic controls for conditioning the machine, at the will of an operator, either to carry out or to exclude, during the performance of one of its functions, the performance of all or part of its other functions.

This application is a continuation-in-part of our co-pending application Serial No. 99,081, filed on June 14, 1949, now Patent No. 2,696,945, and relates to a further improvement in accounting machines of the type defined in Patent No. 2,496,357 which issued on February 7, 1950, on application which was copending with the above.

A further object is to provide an accounting machine having calculating mechanism including actuators paired with corresponding adding type carriers, in which the actuator and type carrier in each pair have independent and relative movement in the operation of the machine.

Another object is to provide an accounting machine having calculating mechanism including actuators and a cycling operating member therefor, wherein the actuators operate under spring tension derived from the operating member in the course of its cycle movement.

Still another object is to provide an accounting machine having adding type carriers movable into and out of printing position relative to a platen, and a cycling operating member, wherein the type carriers are moved under spring tension derived from the operating member in the course of its cycle movement.

A further object is to provide an accounting machine having a visible front strike typing machine and adding type printing means operative from the same keys on a single keyboard common to both to print at a printing point common to both.

A still further object is to provide in an accounting machine having adding type carriers movable into and out of printing position and a single hammer common to a plurality of the carriers, means for holding out of printing position all adding type carriers to the left of those comprising an item to be printed.

Other objects will be apparent to those skilled in the art.

In the accompanying drawings:

Figure 1 is a top plan view of the machine;

Figure 2 is a side elevation with the front part of the main frame removed for illustration of detail;

Figure 3 is a horizontal section substantially on the line 3—3 of Figure 1;

Figure 4 is a vertical section substantially on the line 4—4 of Figure 1;

2

Figure 5 is a vertical section substantially on the line 5—5 of Figure 1;

Figure 6 is a bottom plan view of levers 180 and associated parts;

- 5 Figure 7 is an end view on the line 7—7 of Figure 6;
Figure 8 is a perspective view of latch fingers employed in connection with the adding type bar operation;
Figure 9 is a fragmentary view showing a modification in the structure shown in Figures 4 and 5; and
10 Figure 10 is a top plan view through an interior portion of the machine.

As indicated generally in Figures 1 and 2, the apparatus essentially comprises a main frame 40 of the general form and structure of a typewriter frame, being provided with a keyboard and having a carriage assembly C mounted on the frame for reciprocation in the usual manner of typewriter and posting machine carriage operation.

- The machine is equipped with a bank of front strike type bars 41 operated from keys 42 for front strike visible 20 printing at a point determined by a type guide 43 which forms part of a hammer member 44 that operates in a manner later described to effect a common striking movement against a properly positioned series of adding type bars when they are disposed for printing. The keyboard 25 has the usual spacer 45 and, at the right hand side of the frame, a motor bar 46. On the left hand side of the frame is disposed a tabulator bar 47. The front plate of the frame mounts keys for controlling the functions of calculating mechanism generally indicated at A. These 30 keys at the right hand side of the frame comprise an adding key 48, a total key 49, a subtotal key 50 and, at the left hand side of the frame, a subtract key 51. The type guide 43 establishes the printing point and establishes also the decimal point for item printing in the calculating 35 machine operation. The carriage is provided at its left hand end with a forwardly directed return handle 52 which is substantially of conventional design and which may be rotated to effect line spacing in the usual manner of such devices.

- 40 An essential part of the machine is embodied in a driven reciprocable element which operates through a defined cycle between limit positions in one of which it is at rest, under the influence of motor means to accomplish many functions and to effect the positioning and actuation of the various members and instrumentalities by which the different operations of the associated mechanisms are carried out. This member, herein referred to as an operating frame generally designated at O, provides for the actuation of the various instrumentalities after the machine has been conditioned for their proper sequential operation. 45 It is an important aspect of this invention that, for the greater part, the operation of the various levers, detents, and actuators is under the influence of springs, whereby the various elements are biased or urged into operating movement that is normally restrained by the withholding 50 action of other elements movable under the influence of the operating frame to permit operation of the various levers, detents, and actuators under the influence of their springs. This relieves the motor of a very considerable load, and not only assures fast, smooth operation of the machine but also eliminates to a major extent any possibility of breakage in the event of jamming. Should something occur to jam any parts of the mechanism, the affected parts will not be moved under a force greater than that exerted by their associated springs.

Printing control from calculating unit

- The calculating unit, generally indicated as at A in Figure 1, embodies a plurality of conventional calculator actuators, here shown as slides 142, one for each digit of the calculating unit, which reciprocate horizontally in 55 a frame structure 143 that extends rearwardly from the rear end of the main frame 40 on the base plate 112.

The frame 143 is so positioned relative to the general assembly that the printing point at the type guide 43 is disposed substantially between the second and third digits of the adding type bar assembly.

Each actuator of the calculating unit is provided with an abutment 144 positioned rearwardly of the stop pin box assembly for engagement by one of the stop pins 132', when positioned, so that forward movement of the actuator is arrested at the proper point determined by the numeral key. Common in the operation of adding machines generally, the zeros of the adding type bars all are brought to striking position at the start of a printing operation. In the machine of this invention the adding type bars are held against movement to striking position until the calculator actuators have moved beyond their zero position. Because of the fact that in the present machine a plurality of adding type bars are struck simultaneously by a hammer common thereto, means is necessary to prevent printing of zeros to the left of items printed by impact of the hammer. In machines in which the adding type bars are struck by individual hammers the withholding of type bars to the left is not necessary because those bars are not struck except when the appropriate hammer is actuated.

The machine incorporates in its stop pin box assembly the usual slide plate 145 between the stops 144 and shoulders 146 on the calculator slides. It is activated in the conventional manner from the stop box lug 147 which pivots the slide at 148.

A highly important feature of the invention is the flexible control of the adding type bar action from actuators of the calculating unit. At the start of a printing operation, the actuators move through a part of their travel independently of any operation of the adding type bars. At a predetermined point in the line of travel those actuators permitted to move beyond zero position engage and release spring biased latch means normally holding the adding type bars anchored against movement to striking position. This release is effective only as to the type bars associated with those calculator actuators which have moved beyond their zero position. All others are held against movement except the type bars to the right of any actuator that has gone beyond zero position. Actual movement of the released type bars to striking position is effected by means movable in response to a bias derived from movement of the operating frame.

Movement of the calculator actuators derives from that of the operating frame and is initiated through a spring bias that becomes effective upon the release of restraining means. The restraining means, herein embodied in an actuator restore bar, later described, is movable to release position by propulsion from the operating frame at a predetermined point in one direction of its travel. Propulsion of the restraining means acts against the tension of spring means biasing the restraining means to operative position. The bias of the spring means which urges the restraining means to operative position is utilized to return the adding type bars from printing position during movement of the operating frame in an opposite direction, jointly with restoration of the calculator actuators to initial position. The restraining means in moving back to its operative position acts through the calculator actuators to return the adding type bars toward their initial latched position. Modulating means operative from the restraining means acts at the same time on the type bar moving means to accelerate the movement of the adding type bars relative to that of the calculator actuators so that, when the operating frame comes to rest, the calculator actuators will be out of engagement with the adding type bar moving means, and the type bar moving means will again be latched to hold the type bars at the extreme limit of their travel out of printing position.

Each adding type bar comprises a shank 149 that is vertically slidable for reciprocation in the adding type

bar frame 89, which includes a front plate and rearwardly extended side plates 150. Within the adding type bar frame there are disposed a plurality of followers 151 each of which receives in camming engagement the forward disk-shaped terminal 152 of its associated moving means 153, here shown as a bell crank actuator. One such actuator is provided for each adding type bar. It comprises a bell crank lever having a relatively long forward arm 154 and a shorter rear arm 155. The respective bell crank actuators 153 are pivotally supported from a shaft 156 that is mounted transversely in the frame 143. The arrangement of bell crank actuators, adding type bars, and followers, is substantially that as shown in Patent No. 2,496,357, to Clifton King Rainey of February 7, 1950. The function of each bell crank actuator 153 is to shift its adding type bar 149 into and out of platen striking position. Normally, during index operation of the numeral keys, all adding type bars are in their lowermost position with their bell crank actuators 153 latched in the position indicated in Figures 4 and 5. In this position of the parts the lift arms 154 of the actuators 153 are all held down by a transverse yoke 157 that straddles the upper edges of the crank lever arms. At each end the yoke 157 has fixed connection with a substantially triangular plate 158 that is pivoted at its apex portion on the shaft 156. The plates 158 with the attached holding down yoke are urged to move in a clockwise direction through the agency of a pull rod 159 that is pivotally connected at its forward end to the lower end portion of the triangular plate and which at its rear end has axially slidable connection with an element of the restore bar 160, later to be described. The rear ends of the rods 159 extend rearwardly beyond the restore bar and are provided with take-up adjusting means comprising nuts 161 threaded on the ends of each bar and bearing against a spacer sleeve 162 that contacts the restore bar, so that rearward movement of the bar 160 is transmitted to the pull rods 159 for pull down movement of the plates 158 and hold down yoke 157. The triangular-shaped plates 158 are normally urged to move counterclockwise through the medium of a light spring 163 that is connected to one of the plates 158 and to a finger bracket mounted in an element of the main frame.

After the adding type bars have been indexed by operation of the numeral keys, as previously described, the items provided by the indexing are ready for printing. This printing operation is accomplished during the cycling operation of a member mounted for reciprocation in the main frame and which transmits the necessary operating movement to the parts. This member, which is the operating frame O, consists of parallel side plates forming a right hand side plate R and a left hand side plate L which are spaced apart and connected as a rigid unit by a transversely extended front bar 165 and a transversely extended rear bar 166. This frame is reciprocated horizontally in the main frame between its limit positions in a cycling operation under the influence of an electric motor with clutch mechanism indicated generally at 167. The motor and clutch assembly is secured to the main frame preferably on the left hand side thereof, and when the motor is actuated by depression of the keyboard motor bar 46 it functions to impart rotation to a main drive shaft 168 that is journaled transversely of the main frame between the sides thereof. The drive shaft 168 is rotated in a clockwise direction with respect to Figures 4 and 5. The side plates of the operating frame O are provided with forward end extensions to which are secured, on their inner faces, vertically disposed heads 169 each of which is formed with a vertical closed end slot 170. This slot is intersected intermediate its ends by a horizontal slot 171 that is closed at its rear end and open at its forward end into the vertical slot. The vertical slot constitutes a guideway for a cross head 172 which mounts a laterally extending stud 173 connected to a crank 174 secured to and rotatable with the driving shaft 168. With reference particularly to Fig-

ure 3, it will be seen that as the main shaft 168 is rotated, the crank 174 through its cross head 172 acts to move the operating frame O horizontally forward relative to the front of the machine through one half its operating cycle, and to move the frame horizontally rearward through the other half of its operating cycle.

With the parts in the position illustrated in Figures 3, 4 and 5, the operating frame O is at its rearmost limit and is in position for the initiation of an operating cycle. The front cross bar 165 of the frame has secured thereto a forwardly projected plate 175 that has a portion 176 inclined upwardly and forwardly to merge with a forwardly and horizontally directed lip 177 which at its forward end is formed with an integral upstanding ear 178. A separate retracting spring 179 is connected between the ear 178 and the short arm 155 of each bell crank actuator 153. The bias of this spring is such that as the operating frame moves forwardly during the first half of its cycle the spring is tensioned to bias the actuator 153 for rotation on its pivot in a direction clockwise with respect to Figures 4 and 5. Rocking movement of the bell crank actuator for each adding type bar is normally prevented by latch means 180. In this embodiment of the invention this latch means comprises, for each adding type bar actuator 153, a thin planar finger that is flat in a vertical plane and which underlies its associated actuator 153 in vertical registry therewith. Each finger 180 is pivotally mounted at its rear end on a bearing shaft 181 that is supported at each end in a mounting bracket 182 which is in turn fixed to the adjacent side plate of the calculating unit frame 143. The shaft 181 extends transversely between the sides of the frame 143 and occupies a position slightly forward of the rear edge of the bracket 182. Each finger normally is urged upwardly to rock clockwise on its pivot, with respect to Figures 4 and 5, through the bias of a spring 183 that is connected at one end to a transverse mounting bar 184 extending between and positioned in the brackets 182 beneath the bank of fingers. Each spring 183 at its other and rear end is connected to an ear 185 that depends from the rear end portion of its finger 180. Upward rocking movement of each finger has a limit position that is determined by the engagement of its flat upper edge against the bottom of a thin horizontal plate 186 that overrides the bank of fingers and which is secured at its ends in the brackets 182. Forwardly of the plate 186, which functions as a stop member, each finger 180 carries an upstanding detent 187 that is substantially triangular-shaped to provide an apex portion engageable in a complementary receiving socket 188 formed in the periphery of a disk-like cam head 189 on the lower end of the short arm 155 of the bell crank actuator. The apex portion of the detent 187 is inclined slightly rearwardly so that it functions, when engaged in the socket 188 of the bell crank actuator, as a positive latch which holds the bell crank actuator against movement on its pivot shaft 156. As best shown in Figure 4, in this normal position of the parts the head 189 of the bell crank actuator arm 155 is disposed slightly to the rear of a vertical shoulder 190 constituting the rear vertical edge of an insert 191 that is secured between the front ends of a pair of horizontally extended parallel side pieces 192 which, at their rear ends, are secured to the opposite side faces of a forward extension 193 of the associated calculator actuator slide 142. The side members 192 provide between them a guideway for the disk-shaped head 189 of the bell crank actuator arm 155, so that there is no possibility of side sway during the operation of the bell crank actuator. These side members also provide a guide which confines movement of the finger detent 187 to a true vertical plane for cooperation with the actuator head 189.

The insert 191 at the front end of the side members 192 is provided with a forwardly directed ear to which is attached one end of a coil retracting spring 194 that is connected at its outer and forward end to the upstanding bar 178 of the plate 175 fixed to the front bar 165 of the

reciprocable operating frame O. Normally, prior to the start of a cycling operation, the springs 179 and 194 are only slightly under tension. As the operating frame moves forwardly through the first half of its cycle these springs are placed under increasing tension. The tension on the springs 194 acts to pull forwardly, in the case of each spring, its associated calculator slide 142 until forward movement of the slide is arrested by the holding action of any of the different instrumentalities which may come into play to arrest forward movement of the slide at a proper point. One such arresting means may be a stop pin 132 set in the stop pin box by operation of the indexing means. Another such arresting means may be that which is inherent to the operation of the slides in connection with their associated rack mechanisms forming a part of the calculator mechanism.

When any calculator slide 142 is arrested during the course of its forward movement the continued independent forward movement of the operating frame then increases the tension on the associated spring 194 until the operating frame has reached the forward limit of its travel. In the case of those slides permitted movement beyond zero position by any of the different types of arresting means, that is, slides which function in the operation of printing an item, forward movement will continue under the pull of the springs 194 until the leading bottom edge of the appropriate insert 191 rides upon and cams downwardly the inclined upper edge 195 of an upstanding head 196 on the front end of each finger 180. As the camming action continues, the appropriate finger 180 will be depressed sufficiently to disengage its detent 187 from the associated socket 188 of the adding type bar actuator 153, whereupon, under the tension of the spring 179, the actuator will be rocked on its pivot to move the head 189 of its short arm 155 into contact with the rear vertical edge of the insert 191. Forward movement of the slide under the influence of its associated spring 194 continues to the point at which the movement of the slide is arrested by any of the arresting means previously described. When in finally arrested position, the slide is so disposed that its paired actuator 153 will have been rotated sufficiently on its pivotal support to elevate the cam head 152 of its long arm 154 to lift its associated adding type bar to its striking elevation for printing.

Particularly with reference to Figures 6, 7 and 8, it will be noted that each finger 180, except that at the extreme left hand of the bank of fingers, is provided with a laterally directed integral plate lug 197 which immediately underlies the next adjacent finger of the series in the direction to the left, as viewed with respect to Figure 7. The plate lugs 197 are staggered on their respective fingers, as shown in Figure 6, so that there will be no interference in their operation. By reason of this construction it will be apparent that when any finger of the series to the left of the right hand finger, viewed with respect to Figure 7, is depressed, it will in turn, through the chain of plate lugs on the other fingers, carry down with it all fingers to its right, so that their associated slides 142 may function by movement to their appropriate positions.

Add type bar printing mechanism

During forward movement of the operating frame O in the first half of its cycle, the main shaft 168 operating from the motor and clutch assembly, will have correspondingly rotated a pair of snail cams 198 affixed to the shaft for rotation therewith. The location of these cams is such that they are engaged with the forward edge portions of the hammer carrier levers 199 at their lower end portions. These hammer carrier levers 199, and the associated parts which function in the striking movement of the hammer and type bars in the printing operation, are disclosed in detail in Patent No. 2,496,357 of February 7, 1950. Briefly described, this mechanism includes a pair of the hammer carrier levers 199, each

of which is pivoted intermediate its ends for oscillation in a vertical plane in the printing bar mounting frame 150. At their upper ends the levers 199 are connected by the transversely extended hammer 44 which carries the type guide 43. The lower ends of the hammer levers are biased to move in a direction which imparts striking action to the hammer by the tension of coil spring means 200 connected between a point on the main frame and the intermediate portion of a cross bar 201 carried by and between the lower ends of the hammer levers. As the cams 198 arrive in proper position, their high points 202 slip past a shoulder 203 on the forward edge of each hammer lever and trigger the hammer levers for snap movement in a striking action under the influence of the spring means 200. This striking action of the hammer cannot take place until the adding type bars have been positioned for printing action under the influence of their respective bell crank actuators 153. One complete operating cycle of the frame O is effected simultaneously with one complete revolution of the main shaft 168. In consequence, when the high point 202 of each cam returns to its initial position, as shown in Figures 4 and 5, a diametrically opposed dwell portion of each cam is engaged with the forward edge of each hammer lever 199 in a manner to position the hammer levers as shown in Figures 4 and 5. In this position of the hammer and hammer levers, the hammer clears the platen so that normal operation of the letter keys may take place with the type bars striking through the type guide 43 without interference from the hammer.

The restore bar

With reference particularly to Figures 3, 4 and 5, it will be seen that the restore bar 160 is mounted for reciprocation forwardly and rearwardly in the assembly and is carried by the operating frame. The bar 160 extends transversely between the side plates of the operating frame and is supported slidably on the upper edges thereof by attached saddle blocks 450 which straddle the upper edges of the sides of the operating frame. The restore bar is rectangular in cross section and is attached in brackets 451 provided with rearwardly directed portions which form connecting points for a bank of springs 452 that extend rearwardly from the brackets 451 to anchor brackets 453 attached to uprights 454 secured to the operating frame at its rear end. The restore bar and operating frame are relatively movable. Normally, the restore bar is retained at its rear limit of travel by adjustable stops 455 that are mounted in the downturned rear ends of brackets 456 which extend forwardly in the assembly and which are anchored at their forward ends to an element of the main frame. Adjustment of the stops 455 determines the rearmost limit of movement of the restore bar. The side edge plates of the operating frame are formed at their upper edges each with a shoulder 457 that is spaced rearwardly with respect to the restore bar when the operating frame is at its rear limit of travel, as best shown in Figure 5. When the operating frame is in a position of rest at its rearmost limit of travel the banks of springs 452 are under tension normally urging the restore bar and rear end of the frame into relative converging movement that is prevented by engagement of the restore bar against the stops 455. When the operating frame starts forward in the first half of its cycle the tension of springs 452 acts to pull the frame forwardly with an initial force that is already in effect before the frame begins to move under the influence of the motor drive shaft 168. This bias materially assists the motor in picking up its operating speed at the start of the operating frame cycle.

The bias of the springs 452 is effective until the operating frame advances forwardly to the point at which its shoulders 457 engage the rear of the restore bar, after which the bar is carried forwardly with the operating frame under positive movement thereby. During the interval required for the operating frame shoulders 457

to engage and begin to move the restore bar, the advance of the frame places the springs 179 and 194 under tension. These are the springs, shown in Figures 4 and 5, which function to move the calculating unit actuator 5 slides 142 and the adding type bar actuators 153 forwardly in their actuation. Tension on the springs 194 operates through the slide extensions to pull the slides 142 forwardly until their leading edge portions contact the rear edge of the restore bar. At this point further forward movement of the slides 142 is at the rate of movement of the operating frame for those slides which are permitted to move forward.

After the completion of indexing and when the operating frame begins to move rearwardly through the second half of its cycle the springs 452 again are brought under tension to pull the restore bar rearwardly following the movement of the operating frame. This movement continues until the restore bar arrives at its rear limit as determined by the setting of the stop members 455. As the restore bar moves rearwardly it carries with it the slides 142 of the calculating mechanism and also it functions through the pull rods 159 to pull down the yoke 157 and its supporting side plates so that the adding type bar lift actuators 153 are returned to their depressed initial position. As previously described in connection with the operation of the calculator slides in the indexing function, the position of rest reached by the actuators 153 when depressed under rearward pull of the yoke 157 is such that the short arms 155 of the actuator bar cranks are disposed rearwardly in spaced relation with respect to the inserts 191 of the extensions of the slides 142, whereby the adding type bars are held in fully retracted position.

Thus the restore bar 160 in moving rearwardly contacts and returns the slides 142 to their normal restored position whereby they are held until the following cycle of operation. The restore bar has downwardly extending brackets containing slots through which each of the rods 159 freely pass. During return movement of the restore bar, these brackets engage spacer sleeves 162 secured to rods 159 by nuts 161 and actuate the rods rearwardly. The rods are pivotally fastened to plates 158 so that the plates rock on their pivots 156 and swing yoke 157, attached to plates 158, in an action to move the type bars over a greater range than that which would result from the movement of their corresponding actuators. The movement resulting from the combination of elements 157, 158 and 159 brings actuators 153 to a position where the cam head 189 is moved beyond shoulder 190 of element 191.

The restore bar 160 has pivotal connection 458 at its left end with its associated saddle block 450 and at its other end is longitudinally slotted to receive slidably the shank of an upstanding securing element 459 carried by the subjacent saddle block 450. By this arrangement the restore bar is permitted a limited rocking movement on its pivot to the extent determined by limits of the slot in its opposite end. The advantage of this arrangement is that, should an obstruction occur during the restoring operation while the calculator slides are moving rearwardly, the restoring bar bearing on the leading edge of a stuck slide would apply no force beyond that of the limit of the springs 452. The stuck slide would become, in effect, a fulcrum point on which the restore bar would rock to permit self-alignment of the sliding saddle block 450.

Not infrequently, in the normal operation of the machine, it is desirable to effect a calculating stroke or other stroke of the machine without raising the type bars 149 to printing position. For this purpose, it is expedient to provide a separate arresting means 500 adapted to be operated independently of the actuating mechanism, as by a key or other typing instrumentality located on the carriage or in cooperative relation therewith for opera-

tion of the latching mechanism in response to a predetermined setting of the machine.

An arresting means of the type described, illustrated in Figure 9, comprises an L-shaped lever 501 having a short arm 502 extending upwardly through an opening 503 in the frame plate 59 in position to be operatively engaged by a control instrumentality or the like. The lever is pivoted between the ends of a horizontally disposed long arm 504 upon a pin 505 extending laterally from an upright stud 506 fixed to the frame. The forward end portion 507 of the arm 504 is inclined downwardly to engage a notched portion 508 formed in the upper downwardly inclined edge portion of the triangular plate 155 at a point forwardly of the shaft 156 upon which it is pivoted.

The lever arm is constantly urged to turn in the counter-clockwise direction about its pivot to engage the end portion 507 within the notch 508 by a coil spring 509 anchored at one end onto the underside of the plate 59 and at the other end through an opening or onto a pin 510 located in the arm 504 to the right of its pivot. When the upright portion 502 is depressed to rock the lever arm in the clockwise direction about its pivot, the end portion 507 is displaced from operative engagement within notch 508 to release the bell crank actuator 153 for normal operation.

It is to be understood that the present disclosure is illustrative and not restricted, in that the invention may be practiced in any form consistent with its scope as claimed.

We claim:

1. In an accounting machine, a main frame, a platen, adding type bars movable to and from printing position relative to the platen, calculating mechanism including actuators corresponding to the adding type bars, an operating member movable in the frame, spring tension means connecting individual type bars and the operating member, holding means carried by the main frame and biased to position preventing movement of said type bars to printing position, spring tension means connecting individual actuators and the operating member, said type bars and their corresponding calculating actuators being independently and relatively movable with and by the operating member through their spring tension connections, and said calculating actuators acting when moved beyond their zero positions to disable said holding means whereby to release the type bars for movement to printing position.

2. In an accounting machine, a main frame, a platen, adding type bars movable to and from printing position relative to the platen, an actuator for each type bar comprising a bell crank lever fulcrumed in the frame with one arm in operating connection with its type bar, an operating member reciprocable in the frame, calculating mechanism including an actuator slide corresponding to each type bar actuator, each slide having a portion adjacent the other arm of its corresponding bell crank lever, said other arm having a terminal cam, an abutment on the calculating slide in the path of movement of the cam, spring means connecting each slide with the operating member and biasing the slides to move with the operating member in one direction of its travel, spring means connecting the cam arm of each bell crank lever with the operating member and biasing the levers to rock with movement of the operating member in said one direction of its travel to move the type bars to printing position, latch means normally engaged with the bell crank levers to hold their cams spaced from the calculating slide abutments with the type bars positioned at the extreme limit of their travel out of printing position, latch release means on each calculating slide operative when the slide moves beyond its zero position to free the associated bell crank lever for movement of its cam into contact with the slide abutment whereby to determine the extent of printing position movement of the correspond-

ing type bar, means operative upon movement of the operating member in the opposite direction to return the calculating slides to initial position, and said return means having an operating connection with the bell crank levers whereby, on return of the calculating slides to initial position, the levers are rocked to carry their cams out of contact with the slide abutments for movement of the type bars to the extreme limit of their travel out of printing position for reengagement of the latch means.

10 3. In an accounting machine having calculating mechanism including actuators, an operating member for said mechanism movable through a full cycle between limit positions in one of which it is at rest, spring means urging said actuators to move independently of and in

15 the direction of travel of the operating member during the first half of its cycle, restraining means on said operating member and movable relative thereto in engagement with the actuators to hold them against such movement during an initial portion of the first half cycle travel of the operating member, spring means biasing the restraining means to operative restraining position, and release means on said operating member operative after an interval of initial travel thereof to engage and move said restraining means with the operating member during the remainder of its first half cycle.

4. In an accounting machine having calculating mechanism including actuators, an operating member for said mechanism movable through a full cycle between limit positions in one of which it is at rest, spring means

30 urging said actuators to move independently of and in the direction of travel of the operating member during its first half cycle, restraining means on the operating member and movable relative thereto in engagement with the actuators to hold them against such movement during an initial portion of the first half cycle travel of the operating member, spring means biasing the restraining means to operative restraining position, release means on said operating member engageable with the restraining means after an interval of initial travel of the operating member to carry the restraining means with and in the direction of travel of the operating member during the remainder of its first half cycle, and said restraining means under the pull of its spring bias engaging and restoring to initial position the calculating actuators during travel of the operating member in its second half cycle.

5. The structure of claim 4, and means for arresting return movement of the restraining means at its initial point of operative engagement with said actuators.

50 6. In an accounting machine having a platen and calculating mechanism including actuators paired with corresponding adding type carriers, an operating member for the calculating mechanism movable through a full cycle between limit positions in one of which it is at rest, means for moving the type carriers into printing position relative to the platen, latch means normally engaged with each type carrier moving means to hold its type carrier at the extreme limit of its travel out of printing position, spring means urging said actuators to

55 move beyond zero position independently of and in the direction of travel of the operating member during its first half cycle, restraining means on the operating member and movable relative thereto in engagement with the actuators to hold them against such movement during an initial portion of the first half cycle travel of the operating member, spring means biasing the restraining means to operative restraining position, means operative to condition certain actuators for movement beyond zero position, means on said operating member effective, after movement thereof beyond said initial portion of its first half cycle travel, to engage and move the restraining means with and in the direction of travel of the operating member during the remainder of its first half cycle whereby to release those actuators conditioned

60 for movement beyond zero position, said actuators when 70

11

moving beyond zero position engaging and releasing their respective type carrier latch means, said restraining means moving, during the second half cycle of the operating member, under the pull of its spring bias to engage and carry back all actuators disposed beyond zero position, means for arresting return movement of the restraining means at its initial point of engagement with all said calculating actuators, and means in operative connection with said restraining means for moving back to initial latched position all type carrier moving means freed by movement of their corresponding calculating actuators beyond zero position.

7. In an accounting machine having a platen, type bars movable to and from printing position relative to said platen and actuators for each type bar shiftable during each cycle of operation to and from positions determined by calculating pinions and stops set by the typing instrumentalities, lever means operatively connected to said type bars for actuating same to and from printing position, means forming a part of said actuator for controlling movement of said lever means while permitting limited relative movement therebetween, means independent of said actuator for latching said lever means against movement to printing position, means on said actuator for inactivating said latching means during a portion of said relative movement of said actuator to release said lever for movement to printing positions controlled by said actuator, and means urging said levers in the direction to raise the type bar to printing position.

8. In an accounting machine having a platen and typing instrumentalities, type bars movable to and from printing position relative to said platen and actuators for each type bar shiftable during each cycle of operation to and from positions determined by calculating pinions and stops set by the typing instrumentalities, lever means operatively connected to said type bars for actuating same to and from printing position, means forming a part of said actuator for controlling movement of said lever means while permitting limited relative movement therebetween, means independent of said actuator for latching said lever means against movement, means on said actuator for inactivating said latching means during a portion of said relative movement of said actuator to release said lever for movement to positions controlled by said actuator, and means forming a part of said latching means for automatically releasing all latching mechanism to one side thereof to release their corresponding levers for movement to positions controlled by their corresponding actuators.

9. In an accounting machine having a platen, type bars movable to and from printing position relative to said platen and actuators for each type bar shiftable during each cycle of operation to and from positions determined by calculating pinions and stops set by the typing instrumentalities, lever means operatively connected to said type bars for actuating same to and from printing position, means forming a part of said actuator for controlling movement of said lever means while permitting limited relative movement therebetween, means independent of said actuator for latching said lever means against movement, means on said actuator for inactivating said latching means during a portion of said relative movement of said actuator to release said lever for movement to positions controlled by said actuator, means constantly urging said levers in the direction to raise the type bar to printing position, other means for latching each of said levers against movement to raise the type bars to printing position, and means responsive to instrumentalities other than the actuators for controlling said other latching means.

10. An accounting machine as claimed in claim 7 in which the operative connection between a lever and its corresponding actuator comprises an actuator a portion of which is formed with an elongate slot therein and a lever having a portion located within the slot to permit

12

relative movement by an amount determined by the length of the slot.

11. An accounting machine as claimed in claim 10 in which the length of the slot in which the portion of the lever is located for relative movement is equivalent to the extent necessary for the actuation of each over its greatest operating range independently of the other.

12. An accounting machine as claimed in claim 7 in which the latching mechanism comprises a lever arm having a pawl extending from one edge portion thereof and a notch in the lever for receiving the pawl in latching engagement, means on the lever arm extending in the path of the actuator whereby the lever arm is rocked in the direction to retract the pawl from the notch responsive to engagement with the actuator during shifting movement beyond position for controlling raising movement of the corresponding type bar to beyond zero position, and means constantly urging the lever arm in the opposite direction to position the pawl in the notch of the type bar operating lever in normal position of adjustment.

13. An accounting machine as claimed in claim 9 in which the other latching means comprises a lever arm pivoted for rocking movement in the direction toward and away from said type bar operating lever, means constantly urging the lever arm to rotate in the direction to bring an edge portion into operative engagement with said type bar operating lever, and means forming a part of said lever arm adapted to be operated for rotating the lever arm about its pivot to retract the end portion from operative engagement with the type bar operating lever to release same for normal movement.

14. In an accounting machine, a platen, a plurality of type bars each having a series of types and movable to advance its types selectively to and return them from printing position relative to the platen, calculating mechanism including a like plurality of reciprocable amount actuators, means to differentially arrest said actuators in their advancing movement from a normal position, an operating connection between each type bar and its corresponding calculator actuator to limit the type-positioning movement of the respective type bars in accordance with the positions of arrest of said actuators, said operating connection permitting the calculator actuator to move to its position of maximum advance independently of any type advancing movement of the type bar, cyclically operable drive means, means operated by said drive means in a cycle of operation of the latter and having a portion to advance said actuators from their normal position to their differential positions of arrest in one part of said cycle and to return them to their normal position in a subsequent part of said cycle, and another portion to advance said type bars in said one part of said cycle in an initially trailing relation to said actuators to positions corresponding to the positions of arrest of said actuators and to return said type bars to their normal positions independently of said actuators in said subsequent part of said cycle.

15. In an accounting machine, a platen, a plurality of type bars movable to transport their type to and from printing position relative to said platen, calculating mechanism including a like plurality of amount differential actuators each movable from a normal position to any of a series of amount differential positions independently of its corresponding type bar and each having means to limit type-positioning movement of said type bar, means to arrest the differential actuators selectively in amount differential positions, means yieldingly urging said differential actuators to move to differential position and means yieldingly urging said type bars to move to printing position, cyclically operable drive means, restoring means normally holding said actuators and said type bars in their normal positions and operable by said drive means in a cycle of operation thereof to permit movement of said actuators to differential positions determined by said arresting means and to permit movement of said type

bars to printing positions, latch means on a fixed element of the frame normally holding the type bars against movement to printing position, and means on each said actuator operative during movement thereof independently of the type bars to operate said latch means to release said type bars for movement in response to said biasing means.

16. In an accounting machine, a platen, a plurality of type bars movable to transport their types to and from printing position relative to said platen, calculating mechanism including a like plurality of amount differential actuators movable from a normal position to any of a series of amount differential positions independently of the type bars and each having means to limit type-positioning movement of a respective one of said type bars to locate in printing position the type corresponding to the amount differential position of the differential actuator, settable differential stop means to arrest said actuators in amount differential positions in amount-entering operations, totalizer pinions cooperable with said differential actuators to receive amount entries therefrom in amount entering operations and to limit differential positioning movement of said actuators in total-taking operations, cyclically operable drive means having portions normally positioning said differential actuators in their normal positions and yieldingly urging said actuators to move to differential positions in a cycle of operation and portions normally holding said type bars with their types out of printing position and yieldingly urging said type bars to move to printing positions during said cycle of operation, and individual means normally restraining each of said type bars against movement to printing position, and means operative by each of said actuators in a portion of its independent movement to differential position to disable the restraining means of a respective type bar and release said type bar for movement to printing position.

17. A machine of the character specified having a platen, a plurality of type bars movable from a normal out-of-printing position to any of a series of printing positions, a printing hammer normally in the path of movement of said type bars to their printing positions, calculating mechanism including a like plurality of amount differential actuators movable from a normal position to any of a series of amount differential positions independently of movement of said type bars from their normal positions and each having means to limit movement of a respective type bar to printing positions corresponding to the differential positions of the differential actuator, a cyclically operable operating means including means to move said hammer out of the path of said type bars during an initial part of a cycle of operation, and means to move said differential actuators from normal position at least to a predetermined one of their differential positions during said initial portion of said cycle and to urge said type bars to move to corresponding printing positions, and means normally holding said type bars in their normal positions and operable by said actuators upon movement of said actuators to said predetermined position and movement of said hammer out of the path of said type bars to release the corresponding type bars to printing positions determined by the respective differential actuators.

18. In an accounting machine, a main frame, a platen, a plurality of type bars movable from a normal out-of-printing position to any of a series of printing positions relative to the platen, an actuator for each type bar, an operating member reciprocable in the frame, calculating mechanism including a like plurality of calculating actuators movable from a normal position to any of a series of amount differential positions independently of movement of the type bars from normal, each having an abutment in the path of movement of a respective type bar actuator, spring means urging each calculator actuator to operated position, spring means urging each type bar

actuator to move its type bar to printing position, latch means normally engaged with the type bar actuators to hold them spaced from the calculating actuator abutments with the type bars located in said out-of-printing position, latch release means on each calculating actuator operative upon movement of the calculator actuator beyond a predetermined amount differential position to free the associated type bar actuator for movement into contact with the respective calculator actuator abutment whereby to position its type bar in a printing position corresponding to the differential position of the respective calculating actuator, means on said operating member normally holding said calculating actuators in their normal positions and operative during movement of the operating member in one direction to permit movement of said calculating actuators to differential amount positions and upon movement of said operating member in the opposite direction to return the calculating actuators to normal position, and said last-named means having portions normally holding the type bar actuators in their normal positions and operated upon movement of said operating member in said one direction to permit movement of said type bar actuators into engagement with said abutments and, upon movement of said operating member in said opposite direction, to move the type bar actuators out of contact with the calculator actuator abutments to their normal positions for re-engagement by the latch means.

19. A machine of the character specified having a platen, a plurality of type bars movable from a normal out-of-printing position to any of a series of printing positions, a printing hammer normally in the path of movement of said type bars to their printing positions, calculating mechanism including a like plurality of amount differential actuators movable from a normal position to any of a series of amount differential positions independently of movement of said type bars from their normal positions and each having means to limit movement of a respective type bar to printing positions corresponding to the differential positions of the differential actuator, and a cyclically operable operating means including means to move said hammer out of the path of said type bars during an initial part of a cycle of operation, means normally holding said differential actuators in their normal positions and acting during said initial portion of said cycle to move said differential actuators from normal position at least to a predetermined one of their differential positions and to urge said type bars to move to corresponding printing positions, and means normally holding said type bars in their normal positions and acting during the immediately following portion of said cycle after movement of said hammer out of the path of said type bars to release the corresponding type bars to printing positions determined by the respective differential actuators.

20. In an accounting machine, a main frame, a platen, adding type bars each having a series of types and movable from a normal non-printing position when all of the types are out of printing position relative to platen to place any of its types in printing position, typewriter type bars operable to effect printing strokes against said platen, calculating mechanism including calculating actuators each movable from a normal position to any of a series of amount differential positions and each having means to limit type positioning movement of a respective adding type bar in accordance with the amount differential position of said calculating actuator, a type guide for the typewriter type bars normally lying in the path of movement of the adding type bars to printing position and movable to a position out of said path, a cycling mechanism in the main frame for moving the type guide to the latter position, to move the calculating actuators from their normal positions toward differential positions and to urge the adding type bars to move to printing position during an initial portion of a cycle of operation, and

means to delay movement of the adding type bars to printing position during at least a portion of the movement of said calculating actuators to differential positions and until the type guide has been displaced from the path of movement of the type bars to printing position.

21. In a machine according to claim 16, means settable to hold all of said type bars against movement to printing position throughout movement of the amount differential actuators from normal position to amount differential positions and back to normal position in said cycle of operation of said drive means.

22. In an accounting machine, a main frame, a platen, adding type bars movable from a normal non-printing position to any of a series of printing positions relative to said platen, a movable printing hammer normally in the path of movement of said type bars, calculating mechanism including actuators corresponding to said type bars and each movable independently of said type bars from a normal position to any of a series of differential positions and each having means to limit movement of a respective type bar to printing positions corresponding of the differential positions of said actuator, means for urging said type bars from their position of rest to their position for printing, cyclically operable mechanism having portions for moving said actuators from normal position to differential position and against normal position and to move said hammer from the path of said type bars during an initial part of the movement of said actuators from normal and portions acting during a part of movement of said actuators subsequent to said initial part for releasing said type bars for movement to printing positions at which they are arrested by said limit means and again return said type bars to their normal positions.

23. In an accounting machine, a plural order series of differential actuators controlled by the calculating mechanism mounted for shifting movement to at least zero position during each cycle of operation of the machine, a plural order printing mechanism comprising a single printing hammer and, for each order, an adding type printing element shiftable between normal position out of the path of the hammer to a position for printing in the path of the hammer under control of the actuator of corresponding order, means urging said type printing element into position for printing, latching means operatively engaging said type printing element for holding same against movement from normal position, and means responsive to movement of the actuator beyond a predetermined position for rendering said latching means ineffective to release said type printing element for movement under control of the actuator into the path of the hammer for printing, and a means operative during the cycle of operation for returning all said type printing elements to normal position independently of the actuator and in advance of return movement thereof.

24. In an accounting machine, a plural order series of differential actuators controlled by calculator mechanism for movement to at least zero position and return during each cycle of operation of the machine, a plural order printing mechanism comprising a single printing hammer and, for each order, an adding type printing element shiftable into and out of the path of the hammer for printing, a bell crank lever pivoted intermediate its ends having one end operatively engaging said type printing element for actuation into and out of printing position, means to urge said bell crank lever for pivotal movement in the direction to raise the type printing element to printing position, latching mechanism for holding said bell crank lever against pivotal movement including a lever arm mounted for rocking movement, means on said lever arm for blocking rotational movement of said bell crank lever when in normal position of adjustment, means urging said lever arm in the direction to position said means in blocking position, means on said lever arm adapted to be engaged by the actuator upon movement beyond zero position for rocking said lever arm in the direction to

render said blocking means ineffective and release the bell crank lever for rotational movement.

25. An accounting machine having a plural order differential mechanism comprising, for each order, a differential actuator operable from a normal position to any of a series of differential advanced positions and again to normal position in a machine cycle, and a printing mechanism comprising a single printing hammer, means to impel said hammer in a printing stroke, and, for each of said orders, a printing type bar having a series of types thereon, said type bars being normally positioned out of the path of said hammer, means to advance said type bars from said normal position to positions in the path of said hammer determined by the differential actuators of corresponding orders to position selected types at a printing line, and means for each type bar normally latching said type bar against movement into the path of said hammer and operable by the actuator of corresponding order advancing from normal position to or beyond a predetermined one of said series of differential advanced positions to release the type bar of the same order for movement into the path of the hammer.

26. An accounting machine having a plural order differential mechanism comprising a plurality of differential actuators operable from a normal position to any of a series of differential digital positions and again to normal position in a machine cycle, and a plural order printing mechanism comprising a single printing hammer, means to impel said hammer in a printing impact stroke, a plurality of printing type bars each having thereon a series of digit types including a "0" type, said type bars being normally positioned out of the path of said hammer, means to advance said type bars from said normal position to positions in the path of said hammer determined by the differentially positioned actuators to position selected types at a printing line, and means normally latching said type bars against movement into the path of said hammer and operable by any differential actuators advancing from normal position to or beyond a differential digital position other than the "0" position to release the type bars of the same and all lower order for movement into the path of the hammer to place at the printing line types corresponding to the digital positions of the actuators of corresponding orders.

27. An accounting machine having a plural order differential mechanism comprising a plurality of differential actuators operable from a normal position to any of a series of differential digital positions including a "0" position and again to normal position in a machine cycle, and a plural order printing mechanism comprising a single printing hammer, means to impel said hammer in a printing impact stroke, a plurality of printing type bars each having thereon a series of digit types including a "0" type, said type bars being normally positioned out of the path of said hammer, means to advance said type bars from said normal position to positions in the path of said hammer determined by said actuators to position selected types at a printing line, and, for each type bar, a latch means normally latching said type bar against movement into the path of said hammer and operable by the actuator of the corresponding order advancing from normal position to or beyond a predetermined one of said differential positions other than the "0" position to release said type bar for movement into the path of the hammer to place at said printing line the digit type corresponding to the digital position of said actuator, the latch devices for adjacent orders having means operative upon movement of the higher order latch device to releasing position to move the lower order latch device to releasing position to free the type bar of said lower order to move into the path of said hammer and position its "0" type at the printing line if said lower order latch device has not been released by the differential actuator of said lower order.

28. In a machine of the character specified, a platen to

support record material at a printing line, a plural order printing mechanism including, for each order, a type carrier having a series of types extending transversely of said printing line, an indexing device connected with said type carrier, means normally positioning said indexing device and type carrier with all of said types displaced from said printing line and operable to move said indexing device and type carrier to transport the types of said series successively to said printing line, a differential actuator movable independently of said indexing device and type carrier from a normal position to any of a series of advanced positions, means to arrest said actuator at selected ones of said advanced positions, said actuator having means to limit movement of said indexing device and the connected type carrier to position at the printing line that type of the series corresponding to the arrested position of said actuator, and a latch device normally engaging said indexing device and latching it and the connected type carrier in normal position with all types thereon displaced from the printing line but 20

5
10

operable by said actuator upon movement of the latter from its normal position to or beyond a predetermined one of said advanced positions to release said indexing device and connected type carrier for type indexing movement, each pair of adjacent latching devices having means acting upon movement of the higher order latch device of the pair of to move the lower order latch device to releasing position if it has not been so moved by its associated differential actuator.
